UNITED STATES PATENT OFFICE

168,524

OFFICE MACHINE STAND

William Thomas, Los Angeles, Calif.

Application August 4, 1952, Serial No. 20,889

Term of patent 14 years

(Cl. D33—14)

To all whom it may concern:

Be it known that I, William Thomas, a citizen of the United States, residing in Los Angeles, county of Los Angeles, State of California, have invented a new, original, and ornamental Design for an Office Machine Stand, of which the following is a specification, reference being had to the accompanying drawing, forming part thereof.

Figure 1 is a perspective view of an office machine stand embodying my new design.

Figure 2 is a side view thereof.

Figure 3 is an end view.

The broken lines showing are for illustrative purposes only.

I claim:

The ornamental design for an office machine stand, as shown.

WILLIAM THOMAS.
